MIXING MACHINE

Filed Nov. 1, 1928

UNITED STATES PATENT OFFICE

JOHN F. FIELD, OF OWOSSO, MICHIGAN

MIXING MACHINE

Application filed November 1, 1928. Serial No. 316,386.

This invention is an improvement in mixing machines, and the principal object thereof is to provide a simple, novel, and efficient machine for mixing together various ingredients, whereby the ingredients will be thoroughly diffused, said machine being particularly adapted for mixing balanced rations for stock feed; also for mixing cement, fertilizers, and in fact any other materials which must be aerated, dried, mixed in batches, or in proportions by a formula, said machines embodying certain novel features of arrangement and construction as hereinafter set forth.

15 I will explain the invention with reference to the accompanying drawing which illustrates one practical embodiment thereof to enable others to adopt and use the same, and will summarize in the claims the novel features of construction, and novel combinations of parts, for which protection is desired.

In said drawing:—

Fig. 1 is a top plan view of the mill, partly broken away.

25 Fig. 2 is a side elevation thereof, partly broken away.

Fig. 3 is an end elevation thereof, from the hopper end.

Fig. 4 is an end elevation thereof, from the opposite end.

Fig. 5 is an enlarged detail section through the driving mechanism, and the adjacent end of the drum.

Fig. 6 is a detail. My novel mill preferably comprises a revoluble drum 1, having its ends closed by means of castings 5 and 50 bolted thereto as shown in Figs. 5 and 6, said castings being provided with axially disposed hub portions 5^a, 50^a respectively journaled in bearings 3, secured to supporting frames 4 at each end of the drum. The periphery of casting 5 is provided with gear teeth 5^b coaxial with drum 1, said gear teeth meshing with a pinion 6, provided on one side with a hub extension 6^a, the hub extensions being journaled in a bearing 8, attached to the adjacent frame 4. A sprocket 7 is keyed to the outer end of extension 6^a.

Shaft 2 extends axially through drum 1 and castings 5 and 50 said shaft being journaled

in the hub of casting 5 as shown. On the end of shaft 2 extension to drum 1 and adjacent casting 5 are located the driving pulleys 9 and 10 to be rotated by belts not shown in opposite directions, both of said pulleys being loosely mounted on a sleeve 11, (Fig. 5) which is keyed or otherwise secured to shaft 2 and revolves therewith. On the inner ends of the hubs of pulleys 9 and 10 are formed clutch jaws 9^a, 10^a, and between the pulleys is a sliding clutch 12 which is feathered to the sleeve 11 and movable longitudinally thereof by means of a hand lever 13 pivoted to a member 4^a of frame 4. On the outer end of the sleeve 11 is placed a set collar 14. Any other means, however, for reversing the rotation of the shaft 2 may be used. Between pulley 9 and bearing 3 on shaft 2 is keyed a sprocket 15 which drives the sprocket 7 by means of a chain 16 to rotate the drum 1.

Extending into the drum 1, from the opposite end thereof is a fixed open trough 22 coaxial with shaft 2 in which trough a conveyor screw 18, mounted on shaft 2, rotates while drum 1 revolves. As shown in Fig. 6, trough 22 extends through the hub of casting 50, and through the adjacent bearing 3, whereby a continuous, unbroken, passageway is provided into and out of the drum 1, while permitting the drum 1 to rotate around the fixed trough 22 while shaft 2 is likewise rotating. Within the drum 1, are four longitudinally and radially disposed plates 23 attached to the drum at the ends and inner side of the drum, and to each side of which plates are secured a plurality of parallel vanes 24 disposed at an angle to the transverse axis of drum 1, as shown in the drawing, and slanting preferably towards the end casting 50 of the drum.

At the end of drum 1 adjacent casting 50 is located a hopper 17 into which the trough 22 and the shaft 2, carrying the conveyor screw 18, extends whereby the material may be moved in trough 22 by conveyor screw 18 into or out of the drum 1. Preferably the hopper 17 is an integral part of trough 22, but may be made separately, if desired, and arranged to form a continuation of said

trough. In the outer end of hopper 17 is a bearing for the shaft 2. The hopper is provided with an outlet spout 19 in its bottom, which spout may be opened and closed by operating the slideable plate 20. The lower end of spout 19 is provided with a flange to which a bag B may be secured to receive the material discharged from spout 19. A wire screen 21 is placed in the hopper 17 over the conveyor screw 18 to prevent refuse from entering the container when material is being fed into same.

The operation of the mixer is as follows:— The pulleys 9 and 10 are connected to a suitable source of power by means of belts, one being a cross belt to rotate shaft 2 in opposite directions. When the operator throws the clutch 12 into contact with the hub of one pulley, the shaft 2 and screw 18 revolve in the same direction as that pulley, and the material to be mixed is fed into the drum 1, through the hopper 17, the drum 1 being revolved in the opposite direction by means of sprocket 15, chain 16, sprocket 7, spur pinion 6, and gear 5. As the screw 18 feeds the material into the drum 1, the same overflows trough 22 and falls into the interior of the drum and is picked up and mixed by the plates 23, the vanes 24 feeding the material toward the hopper end of the container. When the mixing is completed, the clutch 12 is thrown to lock against the hub of the other pulley, and the rotation of shaft 2 and drum 1 is reversed, and the mixed material in trough 22 is then fed toward the hopper end, and out through the hopper discharge spout 19 into bags B, or other receptacles, the slide door 20 having been opened to permit the discharge.

I do not limit my invention to the exact form shown in the drawing for obviously changes may be made therein within the scope of the claims.

I claim:—

1. A mixing machine comprising a trough; a conveyor screw in said trough; a rotatable drum coaxial with and enclosing the trough; a plurality of longitudinal plates in the drum exterior to the trough, said plates being disposed radially of the drum; angularly disposed vanes on said plates; and clutch means for rotating the drum and screw in opposite directions.

2. In a machine as set forth in claim 1, a hopper at one end of the drum; and said conveyor screw extending into the hopper; a discharge spout at the bottom of the hopper; and means at the end of said spout for attaching a receptacle thereto.

3. A mixing machine comprising an open trough; a shaft extending longitudinally of said trough; a conveyor screw in said trough, mounted on said shaft; a rotatable drum coaxial with and enclosing the trough; a plurality of longitudinal plates in the drum ex-

terior to the trough, said plates being disposed radially of the drum; and angularly disposed parallel vanes on said plates slanting towards one end of the drum; clutch means for rotating the shaft in opposite directions; and means on the shaft for rotating the drum.

4. In a machine as set forth in claim 3, a hopper at one end of the drum; said conveyor screw extending into the hopper; a discharge spout at the bottom of the hopper; means at the end of said spout for attaching a receptacle thereto; and a slideable plate for closing the spout.

5. A mixing machine comprising a frame; a shaft journaled on the frame; a conveyor screw on said shaft; an open trough for said screw; a rotatable drum journaled on said shaft and enclosing the trough; a plurality of longitudinal plates in the drum exterior to the trough, said plates being disposed radially of the drum; angularly disposed parallel vanes on said plates slanting towards one end of the drum; means on the shaft for rotating the drum in the opposite direction to the shaft; and clutch means for rotating the shaft in opposite directions.

6. In a machine as set forth in claim 5, a hopper at one end of the drum; said conveyor screw extending into the hopper; a screen in the hopper above the conveyor screw; a discharge spout in the bottom of the hopper; means at the end of said spout for attaching a receptacle thereto; and a slideable plate for closing the spout.
